UNITED STATES PATENT OFFICE.

SPENCER SPOONER, OF BROOKLYN, NEW YORK, ASSIGNOR TO A. G. JENNINGS & CO., OF SAME PLACE.

DESIGN FOR KNITTED FABRIC.

SPECIFICATION forming part of Design No. 18,927, dated February 12, 1889.

Application filed December 6, 1888. Serial No. 292,835. Term of patent 14 years.

To all whom it may concern:

Be it known that I, SPENCER SPOONER, a citizen of the United States, residing in the city of Brooklyn, county of Kings, and State 5 of New York, have invented and produced a new and original Design for Knitted Fabrics, of which the following is a specification, reference being had to the accompanying drawings, forming part thereof, and in which—

Figure 1 is a face view of a piece of fabric showing my new design. Fig. 2 is a similar view on an enlarged scale, showing the loops or stitches of the fabric.

The letter A in the drawings represents my 15 new and original design, which is composed of a series of alternating rhomboids, *a* *b*, the rhomboids *a* appearing to the eye to be a lighter shade than the rhomboids *b*. As shown, the sides of a light rhomboid, *a*, lie against

the sides of a darker rhomboid, *b*, producing 20 the peculiar effect shown. Each rhomboid contains a series of short projecting rows of ribs, *d d*. The ribs *d d* of the darker rhomboid, *b*, extend in a line at about right angles to the direction of the ribs *d d* of the lighter 25 rhomboid, *a*.

I claim—

The design for the ornamentation of knit fabric herein described, the same consisting of the series of rhomboids *a* *b*, having rows 30 of projecting ribs *d*, the ribs *d* in the rhomboids *a* extending at about right angles to the ribs *d* in the rhomboids *b*, substantially as shown.

SPENCER SPOONER.
